DESIGN FOR A CROSS

Herbert Brandt, Albert Brandt, and Martin
Brandt, Philadelphia, Pa.

Application December 12, 1939, Serial No. 88,848

Term of patent 3½ years

To all whom it may concern:

Be it known that we, Herbert Brandt, Albert Brandt, and Martin Brandt, citizens of the United States, residing at 4900 Rising Sun Avenue, in the city and county of Philadelphia and State of Pennsylvania, have invented a new, original, and ornamental Design for Crosses, of which the following is a specification, reference being had to the accompanying drawing, forming a part thereof.

Fig. 1 is a plan view of a cross showing our new design; and Fig. 2 is a section on the line 2—2 of Fig. 1.

We claim:

The ornamental design for a cross, substantially as shown.

HERBERT BRANDT.
ALBERT BRANDT.
MARTIN BRANDT.
